(57) **CLAIM**

We claim the ornamental design for housing portions of a cam lock, as shown and described.

DESCRIPTION

Reference is made to utility application Serial No. 09/768, 866 filed (concurrently herewith) by Timothy P. Laabs et al entitled Snap-In Mount For Cam Locks And The Like, to which the subject matter of the present application is related, the disclosure of which are incorporated herein by reference.

FIG. 1 is a perspective view of housing portions of a cam lock showing our new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a bottom plan view thereof; and,

FIG. 7 is a top plan view thereof.
